(57) **CLAIM**

We claim the ornamental design for the wrist lanyard, as shown and described.

DESCRIPTION

FIG. 1 is a perspective of our wrist lanyard invention.

FIG. 2 is a front elevation view thereof.

FIG. 3 is a rear elevation view thereof.

FIG. 4 is a left side elevation view thereof.

FIG. 5 is a right side elevation view thereof; and,

FIG. 6 is a perspective view thereof.

The broken lines on the wrist lanyard represent stitching, and are intended to be part of the claimed design. All other broken lines depict environmental structure and form no part of the claimed design.
